By *Sidney Dawson Atty.*

UNITED STATES PATENT OFFICE.

SIDNEY DAWSON, OF CHICAGO, ILLINOIS, ASSIGNOR, BY DIRECT AND MESNE ASSIGNMENTS, TO DAWSON MANUFACTURING COMPANY, OF CHICAGO, ILLINOIS, A CORPORATION OF ILLINOIS.

GREASE-CUP.

1,345,434.

Specification of Letters Patent.

Patented July 6, 1920.

Application filed September 19, 1918. Serial No. 254,736.

To all whom it may concern:

Be it known that I, SIDNEY DAWSON, a citizen of the United States, and a resident of the city of Chicago, in the county of Cook and State of Illinois, have invented certain new and useful Improvements in Grease-Cups; and I do hereby declare that the following is a full, clear, and exact description of the same, reference being had to the accompanying drawings, and to the numerals of reference marked thereon, which form a part of this specification.

This invention pertains to an improved form of grease cup having interfitting interlocking members disposed in the cup cap so that one of said members may be engaged by a squared alining stem secured in the outlet base of the grease cup, to prevent the cap from being accidentally worked off of the base, due to jarring or vibratory actions of the mechanism upon which the grease cup is mounted, said interlocking members affording an arrangement whereby the cap is held in a predetermined adjusted position from which it can only be moved with respect to said base to force oil therefrom, by manually turning the cap and thereby the other of said interfitting interlocking members to overcome the frictional engagement with respect to the member which is held against rotation by the squared base stem.

It is an object of this invention to provide a grease cup adapted to be operated manually only, to cause grease to be ejected therefrom.

Another object of the invention is the construction of a grease cup wherein movably interfitting grease containers are provided with manually releasable interlocking members for preventing one of said containers from accidentally working its way off of the other of said containers.

It is also an object of the invention to provide a force feed grease cup, wherein interfitting members are adapted to be manually rotated with respect to one another to cause grease to be forced from said cup by the telescoping of grease containers forming said cup.

It is furthermore an object of this invention to construct a grease cup comprising interfitting grease containers, one of which is provided with interfitting members adapted to be engaged by a member secured in the other container to prevent a telescoping ac-

tion between said containers except by a manual rotation of the first mentioned container whereby the frictional engagement between the interfitting members is overcome to permit the containers to telescope to cause grease to be ejected from the cup.

It is an important object of the invention to provide a grease cup of simple and effective form wherein the frictional engagement between interfitting members within the cup is adapted to be manually overcome to permit grease to be forced from said cup.

Other and further important objects of this invention will be apparent from the disclosures in the specification and drawings.

The invention (in a preferred form) is illustrated in the drawings and hereinafter more fully described.

On the drawings:

Figure 1 is a central vertical section taken through a grease cup embodying the principles of this invention, showing parts in elevation.

Fig. 2 is a bottom plan view of the grease cup cap.

Fig. 3 is a top plan view of the grease cup base.

Fig. 4 is a side elevation of the interlocking interfitting members of the grease cup cap removed therefrom.

Fig. 5 is a sectional view taken on line 5—5, of Fig. 4.

Fig. 6 is a section taken on line 6—6, of Fig. 5.

As shown on the drawings:

The reference numeral 1, indicates an externally threaded metal container or cup, having integrally formed on the bottom thereof a hollow nut portion 2, of reduced diameter, on the lower end of which is integrally formed an externally threaded mounting tip or shank 3, of a diameter less than that of the nut 2, and provided with an outlet opening or aperture 4, in the lower end thereof. The shank 3, is provided with a chamber or central passage 5, which communicates with a chamber 6, in the nut portion 2. The cup chamber designated by the reference numeral 7, together with the chamber 6, and passage 5, afford a continuous funnel-shaped passage through the integrally connected members forming the base of the device.

Disposed axially within the base of the grease cup is a key comprising a squared

or angular rod or stem 8, having integrally formed on the lower end thereof a brace or spider, embracing a plurality of radially directed ribs, lugs or vanes 9, adapted to be frictionally forced against the inner walls of the nut 2, to rigidly hold the stem 8, axially disposed within the grease cup base and projecting thereabove, as shown in Fig. 1. The ribs 9, afford a plurality of openings 10, between the inner walls of the nut 2, and said ribs, to permit grease from the cup chamber 7, to pass downwardly into the chamber 6, between the respective ribs 9, and out through the shank passage 5, and the opening 4, to the parts to be lubricated.

An interiorly threaded grease container or cap 11, is provided with a closed chambered head or hood 12, integrally formed on the upper end thereof. The cap 11, is removably threaded upon the threaded base container 1, to telescope thereover, with the squared stem 8, projecting centrally through said cap. Rigidly sprung or threaded into the cap 11, or held securely seated therein by friction or other suitable means against the inner surface of the top 13, of the cap 11, is a star or toothed washer or retainer plate 14, having integrally formed centrally therein a downwardly projecting cylindrical locking sleeve or collar comprising a plurality of adjacently disposed flexible strips or springs 15.

Interfitting with or engaged in the outer locking member which embraces the plate 14 and the springs 15, is an inner locking member comprising a cylindrical locking drum, barrel or friction cup 17, closed at one end, which is provided with a square or angular opening 18, through which the key stem 8, projects, when the grease cup is assembled for use as shown in Fig. 1, to hold said inner locking member against rotation. Formed integrally or rigidly secured on the outer peripheral surface of the locking drum 17, are a plurality of spaced projections or detents 19, which act to hold certain of the springs 15, of the cap locking member sprung outwardly, as shown in Fig. 6. With the grease cup assembled as shown in Fig. 1, the frictional locking members act to normally hold the cap 11, from accidentally rotating upwardly on the base, due to jarring or vibratory actions of the mechanism upon which the grease cup may be mounted.

The operation is as follows:

When it is desired to use the grease cup, as described, on an engine or other mechanism requiring lubricating, the base portion 60 is first mounted by threading the shank 3, into a suitable aperture provided in the mechanism for the purpose, by means of a wrench engaging the nut portion 2, to tightly secure the base in a vertical position. The cup chamber 7, and the cap chamber

below the plate 14, may then be filled with grease, after which the cap 11, is threaded upon the exteriorly threaded cup portion 1, with the squared key stem 8, projecting through the squared aperture 18, to hold the inner locking member 17, stationary or against rotation. The outer locking member rigidly secured within the cap 11, is caused to rotate therewith around the inner locking member, as the cap is manually threaded downwardly on the base, thereby causing the springs 15, of the outer locking member to be sprung outwardly as they are brought into frictional engagement with the detents 19, as the manual rotation of the cap and its locking member is continued.

The manual rotative force exerted on the cap 11, is sufficient to overcome the frictional resistance offered by the locking members, so that the downward movement of the cap on the base, causes pressure to be exerted upon the grease within the grease cup, thereby forcing small quantities of the grease through the openings 10, through the chamber 5, and out through the outlet aperture 4, to the parts requiring lubrication, as the grease cup cap is telescoped over the base.

It will thus be seen that the stem 8, in combination with the locking member 17, and the locking member 14—15, afford a means for normally locking or preventing the cap 11, from moving upwardly off of said base due to the jarring and vibratory actions of the mechanism, or other causes. The frictional engagement between the detents 19, and the springs 15, is sufficient to withstand the jarring and vibrating actions of the parts on which the grease cup is mounted, and hold the cap 11, stationary in a predetermined or adjusted position, from which it can be rotatably moved either downwardly or upwardly by manually turning the cap 11, in the desired direction with sufficient force to overcome the frictional locking engagement between the two locking members. The stem 8, also serves as a means for holding the cap aligned with respect to the base.

I am aware that numerous details of construction may be varied through a wide range without departing from the principles of this invention, and I therefore do not purpose limiting the patent granted otherwise than necessitated by the prior art.

I claim as my invention:

1. A grease cup comprising a chambered base having an outlet therein, a squared key axially secured therein and projecting thereabove, a chambered cap rotatably engaged on said base inclosing said key and adapted to be manually operated to move downwardly over said base to force grease contained within said chambers from said outlet as required, a locking member secured

in said cap to be rotated therewith, and a second locking member frictionally engaged therewith adapted to be held stationary by said key to hold said cap stationary in an 5 adjusted position against accidental movement by jarring or other disturbing actions.

2. A grease cup comprising interfitting grease containers, a square alining stem secured in one container, a spring locking member rigidly secured in the other container, and another locking member held 10 against rotation by said stem adapted to lockingly engage said spring locking member.

15 3. A grease cup comprising a base member, a cap member, an angular stem secured to the base member, a locking member in the cap, springs integral therewith, a second locking member within said cap held 20 against rotation by said stem, and means thereon for frictionally engaging said springs to normally hold said cap in a predetermined adjusted position against accidental rotation.

25 4. In a grease cup a base member, a cap member, a squared stem mechanism rigidly secured in said base member adapted to admit grease therpast through the base member, a locking member in the cap member 30 through which the stem mechanism extends to hold the same against rotation, detents formed on said locking member, and a spring locking member rigidly secured in said cap member and surrounding said first 35 mentioned locking member adapted to be frictionally engaged by said detents to normally hold said cap member in an adjusted position on said base member against accidental movement by jarring or other causes.

40 5. A grease cup comprising a base having an outlet opening therein, a key member secured therein adapted to permit passage of grease through said base, a cap adapted to be threaded onto the base, an apertured 45 locking member within the cap to receive the key member therethrough to hold the locking member stationary, and a resilient lock-

ing member secured in said cap and frictionally engaging said apertured locking member to hold said cap against movement 50 on said base, said cap adapted to be manually rotated on said base to force grease through said outlet opening and cause said resilient locking member to frictionally rotate on said apertured locking member. 55

6. A grease cup comprising telescoping base and cap containers, frictionally interfitting locking members within said cap, and a member rigidly secured in said base container and engaging one of said locking members to hold the same stationary to permit the other locking member to be rotated thereon when said cap container is manually rotated.

7. A grease cup comprising an apertured 65 base, a stem secured thereto, a cap movably mounted on said base, a plate rigidly secured therein, resilient strips integral therewith, an apertured locking member disposed between said strips and held stationary by 70 said stem, and detents on said stationary locking member adapted to spring said strips outwardly to lockingly hold said cap in an adjusted position on said base against accidental movement. 75

8. A grease cup embracing interfitting outer and inner locking members, a base member, means secured thereto for removably engaging said inner locking member to hold the same locked against rotation, and 80 a grease container mechanism engaging the outer locking member and said base member, said container mechanism adapted to be manually rotated to rotate said outer locking member on said inner locking member as the container mechanism is telescoped over the base member. 85

In testimony whereof I have hereunto subscribed my name in the presence of two subscribing witnesses.

SIDNEY DAWSON.
